Specification of Letters Patent.

Patented May 3, 1921.

Application filed May 4, 1917. Serial No. 166,341.

To all whom it may concern:

Be it known that we, JOHN W. ESTERLINE and DONALD J. ANGUS, citizens of the United States, residing at Indianapolis, in the 5 county of Marion and State of Indiana, have invented new and useful Improvements in Engine-Starters, of which the following is a specification.

The object of the present invention is to 10 provide an improved starter for internal combustion engines. It comprises, briefly stated, a relatively small electric motor, a spring for storing energy developed by the electric motor, a brake for restraining the 15 spring until such time as the service of the spring is required, means for transmitting motion from the spring to the crankshaft of the internal combustion engine, and controlling devices for the brake and for the 20 circuit of the electric motor.

The foregoing elements and others herein-after described are organized to operate as follows. The main spring is normally or initially wound, and remains under the 25 restraint of the brake mechanism until the operator closes a manually operative electric switch to energize the electric motor. When the motor is thus energized it drives suitable 30 elements that automatically release the brake, and the main spring is thus permitted to turn the crankshaft of the engine to induce combustion in the latter. Assuming that the engine responds promptly to the force of the main spring, the latter spends 35 itself until it becomes fully relaxed, and in the course of such relaxing, other mechanism operates automatically to close a shunt circuit through the motor to relieve the operator from the necessity of keeping the manu- 40 ally operative switch closed. As soon as the main spring is fully relaxed the brake mechanism is automatically applied, but the shunt circuit of the motor remains closed so that the motor may rewind the spring.

45 Suitable speed-reducing gearing transmits rotation from the armature shaft of the motor to one end of the main spring, and in due course the spring is again fully wound. When the rewinding is complete the shunt 50 circuit through the motor is opened automatically by mechanism driven by the motor. This, in a broad sense, completes a normal cycle of operations. If, however,

the crankshaft of the engine should not respond fully to the stress of the starting 55 spring, and complete relaxing of the latter should be thereby prevented, a different sequence of events would follow, as will be explained in due course.

The electric motor that is employed to 60 wind the starting spring is intended to be supplied with electric current from a storage battery. The starting apparatus, in the present instance, is designed primarily for installation in a motor vehicle, and the 65 storage battery that would ordinarily store electrical energy for electric lighting and electric ignition in the vehicle would serve also to supply current to the electric motor of the starting apparatus. In this connection it is to be observed that the electric motor is comparatively small, and, as a result 70 of the great reduction in speed between the motor and the starting spring, the draft of current from the storage battery for 75 winding the spring is very small. Nevertheless, the interval of time between the closing of the manually operative starting switch and the release of the starting spring is almost instantaneous, for it does not include the winding interval.

Of the accompanying drawings, which illustrate what at present is considered the preferred embodiment of the invention:

Figure 1 represents a front view of the 85 starting mechanism, portions thereof being in vertical section as indicated by line 1-1 of Fig. 2.

Fig. 2 represents a longitudinal vertical section in two planes, as indicated by line 90 2-2 of Fig. 1.

Fig. 3 represents a rear elevation of the starting apparatus.

Fig. 4 represents an inverted plan view, partly in section, as indicated by line 4-4 95 of Fig. 3.

Fig. 5 represents a vertical cross section in the plane indicated by line 5-5 of Fig. 2. This figure shows the parts in their normal or initial positions, the spring being fully 100 wound, the brake mechanism being applied to restrain the spring, and the automatic switch for the shunt circuit of the motor being open.

Fig. 6 represents a sectional view similar 105 to the lower part of Fig. 5, showing the

parts in positions indicating that the brake has been released, that the starting spring has become nearly fully relaxed, and that the automatic switch of the shunt motor circuit has been closed.

Fig. 7 represents an elevation, partly in section, of the brake-controlling mechanism in the same condition as that shown by Fig. 6.

Fig. 8 represents a horizontal section through the structure intersected by line 8-8 of Fig. 6.

Fig. 9 represents a diagram of the electric circuit that includes the winding motor.

Fig. 10 represents a sectional view similar to Fig. 5, showing the starting spring as having become fully relaxed, and the brake mechanism as having been reset.

Fig. 11 represents a perspective view of the brake mechanism standing by itself.

Fig. 12 represents a sectional view, on a larger scale, through the automatic switch of the motor circuit, as indicated by line 12-12 of Fig. 10.

Fig. 13 illustrates in section the coupling between the engine crank shaft and the starting shaft.

The same reference characters indicate the same parts wherever they occur.

The several groups of mechanism herein-
mitting rotation from the spring casing. This casing has bearings for the starting shaft 16, said bearings, in the present instance, being of the anti-friction roller type and being indicated at 17, 17. The starting spring 18 may be of the volute type, if desired, and is arranged within a rotatable casing 19, the periphery of which is cylindrical and is utilized as a brake drum to restrain the spring while the latter is being wound and until such time as it is desired to use the spring for effecting a start of the internal-combustion engine. The other principal element of the brake is a flexible band 20. See Fig. 11. The outer end of the spring is anchored to the periphery of the rotatable casing by any suitable means, such as rivets, one of which is indicated at 21 in Figs. 5 and 10. The inner end of the spring is anchored to a rotatable sleeve 22 by suitable means such as screws, one of which is indicated at 23. The spring is wound by its inner end and is unwound by rotation of its outer end, the direction of such rotation being indicated by arrows *a* in Figs. 1, 5 and 10.

Sleeve 22 is formed upon a winding gear 24, and the latter is driven by an electric motor that is indicated as a whole at 25. Referring to Fig. 8, the armature shaft of the motor is indicated at 26. Suitable speed-reducing gearing transmits rotation from shaft 26 to winding gear 24. This gearing includes a driving pinion 27 and a gear 28 meshing therewith, pinion 29 and

gear 30 meshing therewith, and pinion 31 meshing with gear 24. A ratchet wheel 32 is affixed to one of the rotatable elements of said train of gearing and is engaged by a retaining pawl 33 that prevents the spring 70 from driving the motor backward when the motor is idle. The motor 25 is affixed to the main casing 15 as shown by Figs. 1 and 2.

Referring to Figs. 1 and 2, the casing for the starting spring includes a pin-gear 34, in addition to the brake-member 19, the members 19 and 34 being affixed to each other and being, to all intents and purposes a unit excepting in its structural aspect. 80 The member 34 carries a hardened sleeve 35 that is provided with internal ratchet teeth 36. This sleeve constitutes one principal element of a one-way clutch for transmitting rotation from the spring casing 85 to the starting shaft 16. Said clutch includes also pawls 37, and the latter are carried by a sleeve 38 and connected to the latter by pivot pins 39. Sleeve 38 is affixed to shaft 16. The ratchet-engaging portions 90 of the pawls are held normally in engagement with the ratchet sleeve by helical compression springs 40, but when the shaft 16 is being driven by the internal combustion engine, centrifugal force keeps the 95 pawls out of engagement with the ratchet sleeve and thus avoids clicking of the pawls over the teeth 36. For this purpose the pawls are provided with weight-portions 41 that counteract the stress of springs 40. 100 When the forward ends 41 of the pawls are held outward by centrifugal force they do not engage the ratchet teeth 36, because the rear ends of the pawls at such time engage the sleeve 38.

The two ends of brake-band 20 are anchored respectively to pins 42 and 43. These pins are carried by a pair of floating levers 44. The term "floating levers" is used for the reason that the elements 44 do not have any fixed fulcrum but are capable of bodily movement about the axis of shaft 16 in addition to being capable of angular movement for contracting and expanding the brake-band. A pivot pin 45 extends through the levers 44 and connects the latter with a pair of links 46. It is to be observed that the anchoring pin 43 for the trailing end of the brake-band is between pin 45 and pin 42 that anchors the 110 leading end of the brake-band, and that any angular movement of levers 44 about the axis of pin 45 in response to rotative movement of the brake-drum in the direction of arrow *a* will cause additional tightening of the brake-band. However, in order to guard against breaking the starting spring by winding it too tightly, a stop element 47 is arranged to arrest the leading end of the brake-band when the 120

105

110

115

120

125

130

latter is carried a short distance from its normal position by the unwinding tendency of the spring. The arresting of the leading end of the band prevents further tightening of the latter and enables the brake-drum to slip relatively to the band until such time as the brake mechanism is capable of sustaining the applied force of the starting spring, as will be understood after further description.

Links 46 carry a pivot pin 48 upon which is mounted, between the links, a cam roll 49. This roll is arranged to be engaged by the brake-releasing cam 50. Cam 50 is circular excepting that it has two raised portions 51 which are diametrically opposite each other and which act alternately to depress roll 49 to release the brake.

Links 52 are arranged upon pin 48, and, in conjunction with links 46, constitute a toggle mechanism. A pin 53 (see Fig. 7) connects links 52 one with the other. This pin extends through slots 54 formed in a two-part fixture 55. A lever 56 is arranged between the two parts of said fixture as shown by Figs. 2 and 11, and is slotted to receive the pin 53. The fulcrum pin 57 of said lever is affixed to fixture 55. The free end of the lever 56 is arranged to coöperate with a helical compression spring 58. Spring 58 normally holds the brake-band from being dragged by the brake-drum through the following intermediate elements—lever 56, pin 53, links 52, pin 48, links 46, and levers 44; but enables said intermediate connections to yield, if need be, in the direction of arrow *b* (Fig. 5) to permit the leading end of the brake-band to abut against stop element 47 without subjecting the brake-band to excessive tension that might otherwise injure the latter. When links 46 move in the direction of arrow *b*,—cam roll 49, links 52, and pin 53 necessarily move in unison therewith, and it is to permit such movement of pin 53 that the fixture 55 is provided with the slots 54.

Fig. 5 shows the elements in their normal or initial positions, the starting spring being fully wound, the brake being set to restrain said spring, roll 49 being held against the brake-releasing cam by a helical tension spring 59, and the movable elements all being at rest. It will be observed that the axis of pin 48 is above the "dead center" line that intersects the axes of pins 45 and 53, and that any tendency of the links 46 to move in the direction of arrow *b* in response to the drag of the brake drum will result in pressing cam roll 49 more forcibly against its cam. In order to release the brake it is necessary to depress roll 49 until the axis of pin 48 is below the said "dead center" line, this fact being due to the toggle relation of links 46 and 52. The raised portions 51 of the brake-releasing cam are raised suffi-

ciently to depress the roll below the "dead center" line, and the brake cannot be released otherwise.

Roll 49 coöperates with another cam, indicated at 60, which is circular excepting that it has two depressions 61 that are diametrically opposite each other. The relation of the two cams 50, 60, and roll 49, is shown well by Fig. 2. One depression 61 or the other will always be in registration with cam 75 roll 49 when the elements are in their normal position, thus enabling the cam roll to remain above "dead center." Spring 59, though comparatively light, tends continually to reset the brake-applying mechanism 80 in the normal position shown by Fig. 5, and it is to prevent premature resetting that the cam 60 is provided, the high portions of said cam preventing roll 49 rising to the said "dead center" line of the toggle mechanism. 85 While the spring is unwinding to effect a start the drag of the brake-drum on the brake-band holds the brake-applying mechanism in the condition shown by Figs. 6 and 7, thus counteracting the brake-setting stress 90 of spring 59.

Cam 50 is affixed to a sleeve 62, as shown by Fig. 8, and cam 60 is affixed to a sleeve 63. These two sleeves are mounted upon a dead spindle 64 that is mounted in and affixed to 95 the main casing 15. A star-wheel 65 is affixed to sleeve 62 and is arranged to be rotated intermittently by studs 66 carried by the winding gear 24. See Fig. 2. In the present instance there are two such studs. 100 A star-wheel 67 is affixed to sleeve 63 and is arranged to be rotated intermittently by two studs 68 carried by the member 34 of the spring casing. Referring again to Fig. 8, a collar 69 is arranged upon spindle 64 between cams 50 and 60 and is affixed to the spindle. A washer 70 of friction material is interposed between collar 69 and cam 50, and a similar washer is interposed between collar 69 and cam 60. Dished spring-disks 110 71 are arranged upon the spindle and bear against the star wheels 65 and 67 respectively, to keep cams 50 and 60 pressed against the friction washers to prevent over-travel of the star-wheels in consequence of 115 the momentum acquired by their respective pin-gears.

Sleeves 62 and 63 are rotatable independently of each other, the former being driven exclusively by the spring-winding mechanism, and sleeve 63 being driven exclusively by the mechanism that transmits rotation from the outer end of the spring to the starting shaft 16.

Sleeve 62 carries a cam 72 that closes a 125 shunt circuit through the motor 25. The electrical circuit is shown diagrammatically by Fig. 9. In this figure the winding motor is represented conventionally at 25, and the battery that supplies current therefor is in- 130

dicated at 73. One terminal of the battery is connected to one terminal of the motor by wire 74. Wire 75 connects the other terminal of the battery with one side of a manually 5 operative switch 76. This switch, in the case of a motor vehicle, would preferably be arranged within reach of the driver, and would normally be open as shown. When the switch 76 is closed the circuit would be 10 completed to the motor by wire 77, and the complete circuit would then be as follows: battery 73, wire 75, switch 76, wire 77, motor 25, and return wire 74. The circuit through the motor may be otherwise completed 15 through a shunt circuit that includes wire 78, wire 79, and switch 80. This switch is controlled by cam 72, and its function is to keep the circuit closed through the winding motor until the starting spring has been 20 wound to a predetermined maximum degree. In order to facilitate the description, the circuit through operating switch 76 may be termed the starting circuit, and that through the automatic switch 80 may be termed the 25 winding circuit.

Cam 72 is circular excepting that it has two depressions 81 that are diametrically opposite each other. In the present instance it is of the same shape and size as cam 60. 30 As shown by Fig. 12, switch 80 is carried by but insulated from a lever 82 and is arranged to engage stationary contacts 83, 83. Lever 82 is arranged upon a fulcrum stud 84 and carries a cam roll 85 that is arranged 35 to coact with cam 72. Switch 80 is normally held open by a spring, and in the present instance spring 59 is utilized for this purpose as well as for the purpose of applying the brake. The arrangement of the 40 spring to perform these two functions is clearly shown by Figs. 6 and 11. When the several mechanisms are in their normal or initial positions as shown by Fig. 5, one of the depressions 81 of the switch-closing cam 45 stands in registration with cam roll 85 and permits switch 80 to be held open by spring 59.

A normal cycle of operations is as follows. Assuming that the elements are in 50 their normal condition as represented by Fig. 5, the starting spring being fully wound, the brake being applied, switch 80 being open, and all moving parts being at rest, the cycle is started by closing the manually 55 operated starting switch. The starting circuit is thus closed through winding motor 25, and although the starting spring has been, to all intents and purposes, fully wound before the starting circuit is closed, 60 the winding motor will cause a slight excess winding of the spring sufficient to enable one of the studs 66 on the winding gear to turn star-wheel 65 in the direction indicated by arrow *c* (Fig. 5). The angular motion thus 65 imparted to the star-wheel will be sufficient

to move one of the raised portions 51 of the brake-releasing cam into registration with roll 49. If such slight excess winding of the spring should subject the latter to too great stress the brake-band may slip, as hereinbefore explained, to counteract the excess winding. The initial movement of the brake-releasing cam is not accompanied by any movement of lockout cam 60, because the latter receives its motion only from the outer end of the spring, and ordinarily the outer end of the spring would not have to slip far enough to result in any movement of the starting wheel that drives cam 60. 70

When roll 49 has been depressed below 80 "dead center" the drag of the brake-drum upon the brake-band completes the release of the starting spring, the brake mechanism being thereby placed in the condition shown by Figs. 6 and 7. It may be remarked that 85 the braking effect of spring 59 is negligible when the roll 49 is below "dead center"; and while the brake-drum continues to turn in the direction of arrow *a*, under the stress of the starting spring, the brake-setting elements will remain in the position shown by 90 Figs. 6 and 7.

In the course of releasing the brake, as just explained, switch cam 72 is turned far enough to close the winding circuit through 95 switch 80, and the driver may therefore release switch 76 as soon as he is aware that the starting spring has been released. The remainder of the cycle of operations will be controlled without any further effort or at 100 105 tension on the part of the driver.

Even while the outer end of the spring is 110 unwinding to effect a start, the winding motor 25 is winding the inner end of the spring, and such winding continues without interruption until the spring is fully rewound. As soon as the starting spring has spent all 115 its energy and its outer end has been carried slightly beyond the point of complete relaxation by the momentum of the spring casing, the brake will be reset by spring 59 assisted by the recoil of said casing. The depressions 61 in the lockout cam are so located 120 that one of them will be in registration with roll 49 when the starting spring is fully relaxed, as shown by Fig. 10, and consequently there is nothing to prevent the resetting of the brake at such time. It may be assumed 125 that the internal combustion engine has been started by this time and is operating on its own power, and in such case the winding circuit through motor 25 will remain closed until the spring is fully rewound. During the rewinding operation the studs 66 that are carried by winding gear 24 drive cams 50 and 72 intermittently in the direction of arrow *c* (Fig. 5) until the next depression 81 in cam 72 moves into registration with roller 85. When such registration occurs, automatic switch 80 opens in response to the 130

stress of spring 59, and the motor circuit is opened and the cams come to rest again in the positions shown by Fig. 5. This completes the cycle of normal operations. The 5 qualification "normal" is intended to signify prompt starting of the internal combustion engine on its own power in response to the first starting action of the spring 18.

In some cases, as for example when the 10 frictional or other resistance of the internal combustion engine is too great to enable the starting-spring to reach the point of complete relaxation but arrests the starting-shaft 16 at an intermediate point of relaxation, the brake will not be reset, because the lockout cam 60 will not be in position to permit resetting. Nevertheless, the switch 80 will have been closed by its cam 72, and motor 25 will rewind the spring until the next 15 depression 81 permits the automatic switch to open the winding circuit. If in the course of rewinding the spring from an intermediate point of relaxation the engine shaft turns slowly as the winding motor builds up energy in the starting spring, the lockout cam 60 will eventually reach an angular position where one of its depressions will register with roll 49 as shown by Fig. 10. The brake will thereupon be reset, further turning of 20 the engine shaft will be prevented, and the rewinding of the spring will be completed, ending when the next depression in cam 72 permits switch 80 to open.

In every case when the winding circuit of 25 the motor is opened by switch 80 the controlling cams will be in the positions illustrated by Fig. 5, and if the driver desires to make another attempt to start the engine by means of the starting spring, he has merely to close 30 switch 76 again and the result will be either a normal or another abnormal cycle of operations. The cycle may be repeated as many times as may be desired or necessary.

The starter is capable of being mounted so 35 that its shaft 16 will be coaxial with the crank shaft of an internal combustion engine, and Fig. 13 shows coupling means whereby the two shafts are connected in the relation explained. One end portion of the 40 crank shaft is indicated at 86. A coupling member 87 is affixed to the starter shaft 16 and is formed with an annular portion 88 into which the shaft 86 extends. A pin 89 extends radially through shaft 86 and occupies notches 90, 90 formed in the annular portion 88. Rotation is thus transmitted from shaft 16 to member 87, thence to coupling pin 89, and to the crank shaft. This 45 form of coupling is equivalent to a universal-joint, for the clearance between the annular portion 88 and the parts carried by the crank shaft permits a slight angular relation of the two shafts without causing the parts to bind one upon another. The connection between the pin 89 and annular portion 88 is

inclosed in an annular housing made of a single piece of pressed sheet-metal. Said housing comprises an inner flange 91, an outer flange 92, and a web 93 connecting them.

This form of coupling enables the starter to be uncoupled from the crank shaft without unfastening any of the elements of the coupling, the notches 90 permitting the coupling member 87 to be withdrawn from pin 89.

We claim:

1. An engine-starter comprising a rotary member, a starting spring, means connecting one end of said spring with said member to drive the latter, spring-winding mechanism arranged to wind the other end of said spring, friction brake mechanism arranged to restrain, normally, the driving end of said spring, and means arranged to be operated by said winding mechanism to release said brake mechanism.

2. An engine-starter comprising a rotary member, a starting spring, means connecting one end of said spring with said member to drive the latter, spring-winding mechanism arranged to wind the other end of said spring, a rotary friction-brake-member arranged to be driven by said spring, a stationary friction-brake-member arranged to coact with said rotary brake-member to restrain rotation of the latter, brake-applying mechanism arranged to cause, normally, braking coaction of said brake members, and means arranged to be operated by said winding mechanism to counteract such brake-applying action of said brake-applying mechanism.

3. An engine-starter comprising a rotary member, a starting spring, means connecting one end of said spring with said member to drive the latter, spring-winding mechanism arranged to wind the other end of said spring, a rotary brake-drum arranged to be driven by said spring, a stationary friction-brake-member arranged to coact with said drum, brake-applying mechanism arranged to be affected by turning of said drum, when the brake is applied, to amplify the braking action, and means arranged to be operated by said winding mechanism to render said brake-applying mechanism ineffective.

4. An engine-starter comprising a rotary member, a starting spring, means connecting one end of said spring with said member, to drive the latter, spring-winding mechanism arranged to wind the other end of said spring, brake mechanism arranged to restrain, normally, the driving end of said spring, a brake-controller arranged to be driven by the driving end of said spring to restrain said brake mechanism from acting excepting when said spring is in a predetermined state of relaxation, and means arranged to be driven by said winding mecha-

- nism to render said brake-mechanism ineffective.
5. An engine-starter comprising a rotary member, a starting spring, means connecting one end of said spring with said member to drive the latter, spring-winding mechanism arranged to wind the other end of said spring, a friction brake including two co-operative braking members one of which is stationary and the other of which is arranged to be rotated by the driving end of said spring, brake-applying mechanism arranged to act normally to apply said brake, means arranged to be operated by said winding mechanism to render said brake-applying mechanism ineffective, and, controlling means arranged to be operated by the driving end of said spring to prevent said brake-applying mechanism from reapplying the brake until the rotary brake member has turned a predetermined number of revolutions after the release of the brake.
10. An engine-starter comprising a starting spring, a rotary member connected to one end thereof to transmit the starting motion from said spring, friction brake mechanism arranged to restrain said rotary member, means arranged to wind the other end of said spring, and mechanism arranged to be actuated by said winding mechanism to release said brake mechanism in consequence of winding said other end of said spring a predetermined number of revolutions.
15. An engine-starter comprising a starting spring, a rotary member connected to one end thereof to transmit the starting motion from said spring, friction brake mechanism arranged to restrain said rotary member, means arranged to wind the other end of said spring, and mechanism arranged to be actuated by said winding mechanism to release said brake mechanism in consequence of winding said other end of said spring a predetermined number of revolutions.
20. An engine-starter comprising a starting spring, a rotary member connected to one end thereof to transmit the starting motion from said spring, friction brake mechanism arranged to restrain said rotary member, means arranged to wind the other end of said spring, and mechanism arranged to be actuated by said winding mechanism to release said brake mechanism in consequence of winding said other end of said spring a predetermined number of revolutions.
25. An engine-starter comprising a starting spring, a rotary member connected to one end thereof to transmit the starting motion from said spring, friction brake mechanism arranged to restrain said rotary member, means arranged to wind the other end of said spring, and mechanism arranged to be actuated by said winding mechanism to release said brake mechanism in consequence of winding said other end of said spring a predetermined number of revolutions.
30. An engine-starter comprising a starting spring, a rotary member connected to one end thereof to transmit the starting motion from said spring, friction brake mechanism arranged to restrain said rotary member, means arranged to wind the other end of said spring, and mechanism arranged to be actuated by said winding mechanism to release said brake mechanism in consequence of winding said other end of said spring a predetermined number of revolutions.
35. An engine-starter comprising a starting spring, a rotary member connected to one end thereof to transmit the starting motion from said spring, friction brake mechanism arranged to restrain said rotary member, winding mechanism arranged to wind the other end of said spring, said winding mechanism including a gear, and means arranged to release said brake mechanism, said releasing means being arranged to be operated by said gear, in consequence of turning the latter a predetermined number of revolutions.
40. An engine-starter comprising a starting spring, a rotary member connected to one end thereof to transmit the starting motion from said spring, brake mechanism arranged to restrain said rotary member, winding mechanism arranged to wind the other end of said spring, said winding mechanism including an electric motor, mechanism arranged to be actuated by said winding mechanism to release said brake mechanism in consequence of winding said other end of said spring a predetermined number of revolutions, and means arranged to be operated by said winding mechanism to open the circuit of said motor before said releasing mechanism is operated as aforesaid.
45. An engine-starter comprising a starting spring, a rotary member connected to one end thereof to transmit the starting motion from said spring, brake mechanism arranged to restrain said rotary member, winding mechanism arranged to wind the other end of said spring, said winding mechanism including an electric motor, mechanism arranged to be actuated by said winding mechanism to release said brake mechanism in consequence of winding said other end of said spring a predetermined number of revolutions, and means arranged to be operated by said winding mechanism to open the circuit of said motor before said releasing mechanism is operated as aforesaid.
50. An engine-starter comprising a starting spring, a rotary member connected to one end thereof to transmit the starting motion from said spring, brake mechanism arranged to restrain said rotary member, winding mechanism arranged to wind the other end of said spring, said winding mechanism including an electric motor, mechanism arranged to be actuated by said winding mechanism to release said brake mechanism in consequence of winding said other end of said spring a predetermined number of revolutions, and means arranged to be operated by said winding mechanism to open the circuit of said motor before said releasing mechanism is operated as aforesaid.
55. An engine-starter comprising a starting spring, a rotary member connected to one end thereof to transmit the starting motion from said spring, brake mechanism arranged to restrain said rotary member, winding mechanism arranged to wind the other end of said spring, said winding mechanism including an electric motor, mechanism arranged to be actuated by said winding mechanism to release said brake mechanism in consequence of winding said other end of said spring a predetermined number of revolutions, and means arranged to be operated by said winding mechanism to open the circuit of said motor before said releasing mechanism is operated as aforesaid.
60. An engine-starter comprising a starting spring, a rotary member connected to one end thereof to transmit the starting motion from said spring, brake mechanism arranged to restrain said rotary member, winding mechanism arranged to wind the other end of said spring, said winding mechanism including an electric motor, mechanism arranged to be actuated by said winding mechanism to release said brake mechanism in consequence of winding said other end of said spring a predetermined number of revolutions, and means arranged to be operated by said winding mechanism to open the circuit of said motor before said releasing mechanism is operated as aforesaid.
65. An engine-starter comprising a start-

ing spring, means arranged to wind one end thereof, a rotatable brake-drum arranged to be driven by the other end of said spring, a brake-band arranged to coact with said brake-drum, means arranged to tighten said brake-band on said brake-drum, said tightening means being arranged to yield to enable said band to turn with said drum, and a stop arranged in the path of the leading end of said band to relax the latter.

70. An engine-starter comprising a main spring, an electric motor and gearing arranged to wind said spring at one end, a rotatable member connected to the other end of said spring to transmit the starting motion from the spring, brake mechanism arranged to restrain said rotatable member, means arranged to be actuated by said gearing to open the circuit of said motor when the winding of said spring has progressed to a predetermined degree, and means arranged to be actuated by further spring-winding movement of said gearing to move said brake mechanism to release said rotatable member.

75. An engine-starter comprising a main spring, an electric motor and gearing arranged to wind said spring at one end, a rotatable member connected to the other end of said spring to transmit the starting motion from the spring, brake mechanism arranged to restrain said rotatable member, said brake mechanism being arranged to be self-setting excepting while said rotatable member is partaking of starting motion, means arranged to be actuated by said gearing to open the circuit of said motor when the winding of said spring has progressed to a predetermined degree, and means arranged to be actuated by further spring-winding movement of said gearing to move said brake mechanism to release said rotatable member.

80. An engine-starter, a starting spring, mechanism arranged to wind said spring at one end, a rotatable member connected to the other end of said spring to transmit the starting motion from the latter, a brake-drum and a brake-band arranged to coact to restrain said rotatable member, brake-applying mechanism including toggle members, a spring arranged to move said toggle members to "dead center" relation to apply the brake, and means arranged to be actuated by said winding mechanism to displace said toggle members from said "dead center" relation, in opposition to the stress of said toggle-moving spring, in consequence of winding said starting spring to a predetermined degree.

85. An engine-starter, a starting spring, mechanism arranged to wind said spring at one end, a rotatable member connected to the other end of said spring to transmit the starting motion from the latter, brake mechanism arranged to restrain said rotatable member.

- member, means including trip mechanism arranged to hold said brake mechanism in brake-applying position, and a movable element arranged to trip said trip mechanism to release the brake, said movable element being arranged to be actuated for the purpose stated by an element of said winding mechanism in consequence of winding said starting spring to a predetermined degree.
14. In an engine-starter, a starting spring, mechanism including an electric motor arranged to wind said spring at one end, a rotatable member connected to the other end of said spring to transmit the starting motion from the latter, brake mechanism arranged to restrain said rotatable member, means including trip mechanism arranged to hold said brake mechanism in brake-applying position, controlling means arranged to trip said trip mechanism to release the brake, said controlling means being arranged to be actuated for the purpose stated by an element of said winding mechanism in consequence of winding said starting spring to a predetermined degree, and a switch adapted to open and close the circuit of said motor, said controlling means being arranged to operate said switch.
15. An engine-starter comprising a normally wound spring, a motor independent of the engine for storing power in the spring, a spring-driven member for transmitting starting power to the engine shaft, and mechanism normally holding said driven member against movement in a state of rest when the power is stored in the spring sufficiently to start the engine and said spring is in a state of rest and automatically releasing the driven member when the spring is wound farther.
16. An engine-starter comprising a spring, a spring-driven member, a brake arranged to restrain the spring-driven member from rotation in a state of rest when the spring has been stressed to a predetermined extent sufficient to start the engine and is in a state of rest, and mechanism set in action by further stressing the spring to release the brake and permit the spring to relax.
17. An engine-starter comprising a normally wound spring, a motor independent of the engine for winding the spring, a spring-driven member for transmitting starting power from the spring to the engine shaft, and mechanism for automatically stopping the motor and holding the spring from unwinding when the spring has been wound to a predetermined extent.
18. An engine-starter comprising a spring, a spring-winding member, an electric motor for actuating said winding member, a spring-driven member for imparting movement to the crank shaft of the engine, a brake for said spring-driven member, and mechanism for automatically setting said brake when

said spring has been wound by said motor and said winding member.

19. An engine-starter comprising a spring, an electric motor for storing power in said spring, mechanism for transmitting power from the spring to the crank shaft of an engine, and automatic mechanism for stopping the operation of the motor upon completion of winding the spring and for restraining the spring in its wound condition, whereby the parts come to a normal state of rest with power stored in the spring.

20. An engine starter comprising a normally wound spring, mechanism for transmitting power from said spring to the engine, an electric motor for winding said spring, means for normally restraining said spring from unwinding, and adapted to be released under manual control to permit said spring to unwind, and mechanism for automatically causing said motor to operate when said spring is released until it again comes to a state of rest in a wound condition.

21. An engine starter comprising a spring, electrically operated spring-winding means independent of the engine, means normally restraining said spring from unwinding when wound and in a state of rest, and mechanism for releasing said spring to permit the transmission of power to the engine shaft.

22. An engine starter comprising a spring, a spring-driven member, spring-winding mechanism independent of the engine, mechanism for automatically restraining the spring-driven member when the spring has been wound, is in a state of rest, and starting power is stored therein, and mechanism under manual control, for automatically releasing said spring-driven member and causing the operation of the spring-winding mechanism.

23. An engine-starter comprising a spring, a spring-driven member from which power is imparted to the engine, spring-winding mechanism, mechanism for normally restraining said spring-driven member from operation and holding it in a state of rest with the spring in wound condition and in a state of rest, and means for causing said mechanism to release said member on further winding of said spring.

24. An engine-starter comprising a normally wound spring, a spring-driven member, a brake normally holding said member against movement with the spring in wound condition, mechanism for opening the brake upon further winding of said spring, to release the spring and spring-driven member, an electric motor for winding the spring, and mechanism for automatically closing the motor circuit to wind the spring and store power therein when said brake is open.

25. An engine-starter comprising a nor-

5 mally wound spring, a winding member connected to one end of the spring, a spring-driven member connected to the other end of said spring, a friction brake for the driven member, and mechanism operated by the winding member for releasing or opening said brake.

10 26. An engine-starter comprising a normally wound spring, a winding member connected to one end of the spring, a spring-driven member connected to the other end of said spring, a friction brake for the driven member, mechanism operated by the winding member for releasing or opening 15 said brake, and mechanism operated by the spring-driven member for closing said brake on said driven member.

20 27. An engine-starter comprising a spring, an electric motor for winding said spring, a spring-driven member, a brake for holding said driven member against movement with engine-starting power stored in said spring, means for initially closing the motor circuit, and mechanism operated automatically 25 by said electric motor for maintaining the motor circuit closed until the spring is reset in wound condition.

30 28. An engine-starter comprising a normally wound spring, an electric motor for winding said spring and storing engine-starting power therein, a spring-driven member, a brake normally restraining said driven member, means for closing the motor circuit to initiate the operation of the motor, mechanism automatically operated by said motor 35 for also closing the motor circuit, to effect the continued operation of the motor, and mechanism automatically setting the brake when the spring has unwound.

40 29. An engine-starter comprising a normally wound spring, an electric motor for winding said spring and storing engine-starting power therein, a spring-driven member, a brake normally restraining said 45 driven member, motor-actuated means for releasing the brake, a motor circuit including a manually operated switch and an automatic switch arranged in multiple, mechanism operated by the motor for operating

said automatic switch, and mechanism for setting said brake when the spring is relaxed.

55 30. An engine-starter comprising a normally wound spring, a rotatable winding member connected to one end thereof, a rotatable spring-driven member connected to the other end thereof, a brake for the spring-driven member to hold it against rotation with the spring in wound condition, mechanism actuated by the winding mechanism 60 for operating the brake to release the driven member and permit the spring to unwind, and mechanism actuated by the driven member to prevent the setting of the brake until the spring is relaxed.

65 31. An engine-starter comprising a normally wound spring, a motor independent of the engine for winding or stressing the spring to a given point, whereby power is stored therein for starting the engine, means 70 for preventing the spring from unwinding when so stressed or wound, automatic means for stopping the motor when the spring has been so stressed or wound, means to close the motor circuit to start the motor and wind or stress the spring beyond said given point, and mechanism for automatically permitting the spring to unwind when so stressed or wound beyond said given point.

75 32. An engine-starter comprising a normally wound spring, an electric motor for winding or stressing said spring to a given point, means for preventing the spring from unwinding when so stressed or wound, mechanism for automatically releasing said 80 means to permit the spring to unwind when wound or stressed beyond said point, means for automatically breaking the motor circuit when said spring has been stressed or wound to said point, and means under manual control for closing said motor circuit whereby said motor stresses or winds said spring beyond said point.

85 In testimony whereof we have affixed our signatures.

JOHN W. ESTERLINE.
DONALD J. ANGUS.
